DESIGN FOR A PHOTOGRAPHIC POCKET CAMERA

Richmond Rochester, Mountain Lakes, N. J.

Application July 17, 1934, Serial No. 52,608

Term of patent 3½ years

To all whom it may concern:

Be it known that I, RICHMOND ROCHESTER, a citizen of the United States, residing at Mountain Lakes, in the county of Morris and State of New Jersey, have invented a new, original, and ornamental Design for a Photographic Pocket Camera, of which the following is a specification, reference being had to the accompanying drawing, forming part thereof.

Fig. 1 is a plan view of a photographic pocket camera, showing my new design.

Fig. 2 is a side elevation of the same.

I claim:

The ornamental design for a photographic pocket camera, substantially as shown.

RICHMOND ROCHESTER.
